UNITED STATES PATENT OFFICE.

HARRY SAVAGE AND WILLARD LYMAN BAKER, OF SAN ANTONIO, TEXAS.

AUTOMATIC PASSENGER-FARE-REGISTERING MECHANISM.

1,109,790.

Specification of Letters Patent.

Patented Sept. 8, 1914.

Application filed June 10, 1913. Serial No. 772,867.

To all whom it may concern:

Be it known that we, HARRY SAVAGE and WILLARD LYMAN BAKER, citizens of the United States, residing at San Antonio, in the county of Bexar, State of Texas, have 5 invented a new and useful Automatic Passenger - Fare - Registering Mechanism, of which the following is a specification.

The present invention relates to improvements in an automatic fare registering mechanism which is especially adapted for use in connection with rapid transit cars or the like, one object of the invention, being the provision of means actuated due to the stepping 10 upon of a passenger that will operate the fare register in the car or vehicle, there being novel means provided by means of which an electro magnet is operated to operate the register and recorder, in consonance with the depression of the step as the 15 passenger enters the car.

A further object of the invention is the provision of a novel mechanism for operably connecting the fixed step member, which is 20 disposed in an electric circuit either independently of the propulsion circuit or in shunt therewith, and which operates a solenoid or an electro magnet which in turn is operably connected to the register and recorder. 25

With the foregoing and other objects in view which will appear as the description proceeds, the invention resides in the combination and arrangement of parts and in 30 the details of construction hereinafter described and claimed, it being understood that changes in the precise embodiment of the invention herein disclosed can be made within the scope of what is claimed without departing from the spirit of the invention. 35

In the drawings—Figure 1 is an end view of a car with portions thereof in section and broken away, illustrating one method of applying the present apparatus thereto. Fig. 45 2 is one method in diagram of the application of the present invention and in which the propulsion current is controlled to operate the present device. Fig. 3 is a view partially in diagram and partially in section 50 of the main members of the present mechanism. Fig. 4 is a top plan view of the portion carried by the step of the car and the switch. Fig. 5 is a section through the resilient step and the fixed member thereof, 55 showing the switch controlling lever upon an enlarged scale. Fig. 6 is a section taken

on line 6—6 of Fig. 4 showing the switch on an enlarged scale. Fig. 7 is a section taken on line 7—7 of Fig. 6. Fig. 8 is section taken on line 8—8 of Fig. 6. Figs. 9 and 10 60 are diagrams and sectional views showing a modified form of the present invention.

Referring to the drawings, the numeral 1 designates one of the beams of the car to which is properly connected the hangers 2, 65 the fixed step section 3 being pivotally connected thereto so that the same may be placed into extended or collapsed position, the present invention being especially adapted to be applied to the folding car step 70 now in use. The two step sections 4 and 5 are hingedly connected together at one end, so that the upper section 5 will be resiliently supported and normally held in upward position, by means of the cone-shaped helical 75 springs 4', the plate 5' being provided to limit the upward movement of the section 5. The lever actuating pin 6 is carried by the section 5 and projects downwardly to engage 80 the switch operating lever 7, which is pivoted at 8 and supported by the hangers 2, the same being operatively connected to the respective links 9 and 9' which are extended beneath the rear platform of the car, the same being limited in its rearward movement by means of the pin 10 carried by the rear end of the lever 7. The extreme inner end of the link 9' is operably connected to 85 the crank 11 which is keyed upon the transversely mounted shaft 12 carried in the 90 switch block or casing 13.

The shaft 12 within the casing 13 is provided with the cylindrical portion 14 having the two upstanding projections 15, the outer portion of which is curved concentrically to 95 the cylindrical portion 14 and forms a movable contact of an operating electrical circuit as will presently appear. Disposed removably in the cover of the casing, are the two metal sleeves 16, the casing 13 being 100 composed of insulating material so that the shaft 12 will be properly insulated therefrom, and said casing being filled with oil, so that the shaft 12 and its carried parts will be properly lubricated at all times. 105 These socketed members 16 each carry the stud 17, provided with the contact face 18, this face 18 being disposed in line to be engaged at the proper time by means of the projection 15 of the cylindrical portion 14 110 of the shaft 12. A spring 19 holds the contact portion 18 resiliently toward the re-

spective projection 15, while the pin and slot 20 limit the inward movement thereof. Two of these contacts 18 are provided, to insure the proper closure of the circuit, as 5 will presently appear, for when oil is employed and the full mechanism within the casing 13 is immersed therein, there is a tendency to prevent the proper circuiting between the parts 15 and 18, and in case one 10 part 18 only were provided, the circuit connection at the switch might be rendered inoperative. In order to provide a means for automatically returning the shaft 12 and opening the switch members 15, and for 15 maintaining the same in the normal position with the parts as shown in Figs. 1 and 3, a spool 21 is keyed upon the shaft 12 within the casing 13, and has one terminal of the spring 22 connected thereto, while the outer 20 terminal of the spring is connected to the screw eye 23, and in such a position, that the normal tension of the spring is against the inward movement of the crank or arm 11 when the lever 7 is depressed due to the de- 25 pression of the section 5 of the step. This depression will cause the outer end of the lever 7 to be depressed, while the pin 10 will be elevated to engage the link 9, and thus pull upon the link 9' and move the arm or 30 crank 11 forwardly or to the dotted line position as shown in Fig. 3. This action causes the switch projections 15 carried by the shaft 12 to engage the resilient contacts 18 and thus close the circuit to operate the 35 register R. This circuit may be established by a battery circuit within the car, or where the car is electrically operated, may be shunted with the propulsion current similar to the lighting and heating circuits of the 40 car.

In Fig. 2, is illustrated a diagram, in which the propulsion current is employed, and in the present instance, the main fuse 24 which is connected to the propulsion current 45 as it enters the car, has led therefrom the conductor 25, said conductor 25 being connected to the resistance 26, which when the present invention is used with the propulsion current, will reduce the voltage from 50 500 to 110 volts, so that such current led through the conductor 27 to the solenoid 28, will not cause the burning out of the solenoid. The conductor 38 is led from the solenoid to the contacts 18, the circuit being 55 completed through the contacts 18, the projections 15, the shaft 12, the conductor 40 and the ground 41. The solenoid 28 as clearly shown in detail in Fig. 3, is provided with the core 29, which is normally 60 held extended by means of the spring 30. The link 31 is connected to the core and to the lever 32, which is pivoted at 33 intermediate of its ends and is carried by the support 34, which may be positioned any- 65 where within the car so that the link 35

connected to the opposite end of the lever 32 may be operably connected, as clearly shown in Fig. 1, to the arm 36 of the register R. It will thus be seen that when the core 29 is moved inwardly due to the energization 70 of the solenoid 28, that the registering mechanism will be operated. This operation will, as before described, be coincident with the depression of the resiliently supported section 5 of the step, and close the circuit as 75 before mentioned, to energize the solenoid 28, or will close the circuit as clearly shown in diagram in Fig. 3, where the resistance 26', is interposed between the switch point 18 and the solenoid 28 by means of the conductors 38' and 38.

It is apparent that any practical wiring 80 may be used in connection with the switch operated by the section 5 and the solenoid 28, it being essential that when the section 5 is depressed, that the circuit for operating the register R will be energized and as 85 soon as the same has been released, that the step will be automatically returned to release the lever 7, while the spring 22 will 90 assist in opening the switch by operating the shaft 12.

In the form of operating mechanism shown in Figs. 9 and 10, the lever 7' is provided with the pin 10', the short link 42 being connected to the lever 7' and displacing the link 9 heretofore described, while a similar short link 43 is operably connected to the link 42 and is connected to a lever 44, said lever 44 being pivoted intermediate 95 of its ends to the lugs 45, of the bracket 46 supported from the beam 1 of the car. Connected to the upper free end of the lever 44 is a socketed member 47, which receives the pin 48 which, as clearly shown, is operably 100 connected to the lever 11^a, which is similar to the lever 11 for operating the switch device mounted in the casing 13.

In the instances shown in Figs. 9 and 10, the switch 13 is operated against the spring 110 22 and in an opposite direction to that shown in Fig. 8, and heretofore described, the lever or crank 11^a being pushed upon, instead of pulled, at the time the section 5 is depressed. In Fig. 10, the lever 7' and 115 the step sections are shown folded, the sliding connection between the members 47 and 48 permitting this movement without affecting the switch.

By means of the adjustable connection at 120 45 and 46, the lever 44 may be applied to any platform of the present construction of car, without to any extent altering the present device or the car frame.

What is claimed is:

1. A fare registering mechanism, having a step hanger, a hinge carried thereby, a step section connected by said hinging element to the hanger, a lever pivoted to said hinging element, and means for connecting 130

the lever to the step hanger, whereby when the step section is folded the lever is moved therewith, and also by means of which the lever may be operated when the step section is extended.

2. A fare registering mechanism, having a step hanger, a hinge carried thereby, a step section connected by said hinging element to the hanger, a main lever pivoted intermediate of its ends to the hinge and having one terminal disposed substantially parallel to the step section, means connecting such terminal for swinging movement with the step section, a pin carried by the other terminal of the main lever, an auxiliary lever having one end pivoted to the main lever between the hinge and the pin,

and means controlled by the auxiliary lever for operating a registering mechanism, said pin forming a stop for the auxiliary lever 20 when the step section is extended and whereby when the step section is folded and extended, the two levers and the means controlled thereby will not be disarranged or operated. 25

In testimony that we claim the foregoing as our own, we have hereto affixed our signatures in the presence of two witnesses.

HARRY SAVAGE.
WILLARD LYMAN BAKER.
